US00D438869S

(12) **United States Design Patent** (10) Patent No.: **US D438,869 S**
(45) Date of Patent: **** Mar. 13, 2001**

(54) **FACSIMILE MACHINE**

(75) Inventor: **Masahiro Nakamura**, Hiroshima-ken (JP)

(73) Assignee: **Sharp Kabushiki Kaisha**, Osaka (JP)

(**) Term: **14 Years**

(21) Appl. No.: **29/123,294**

(22) Filed: **May 12, 2000**

(30) **Foreign Application Priority Data**

Nov. 12, 1999 (JP) 11-31280

(51) LOC (7) Cl. **16-03**

(52) U.S. Cl. **D14/468**

(58) Field of Search D14/462-471; 358/400, 401, 402, 296, 474, 475, 487

(57) **CLAIM**

The ornamental design for a “facsimile machine”, as shown and described.

DESCRIPTION

FIG. 1 is a top, front and right side perspective view of a facsimile machine according to my design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a bottom plan view thereof.

1 Claim, 7 Drawing Sheets

FIG. 1

FIG. 2

*FIG. 5**FIG. 6*

FIG. 7
